United States Patent Office

Des. 228,292

Patented Sept. 4, 1973

228,292

HOUSING FOR TELEPHONE APPARATUS

Donald Michael Genaro, Haworth, and Daniel Wescoat
Tyler, Middletown, N.J., assignors to Bell Telephone
Laboratories, Incorporated, Berkeley Heights, N.J.

Filed May 21, 1971, Ser. No. 145,988

Term of patent 14 years

Int. Cl. D14—03

U.S. Cl. 26—14 A

FIG. 1

FIG. 2

FIG. 3

FIG. 4

FIG. 1 is a perspective view of our new design for a housing for telephone apparatus;

FIG. 2 is a side view of the housing, the opposite side being substantially a mirror image thereof;

FIG. 3 is a top view of the housing; and

FIG. 4 is a front view of the housing.

The back and bottom of the housing are plain and unornamented.

We claim:

The ornamental design for a housing for telephone apparatus, substantially as shown and described.
